His ATTORNEY.

UNITED STATES PATENT OFFICE

ROBERT N. SMITH, OF KANSAS CITY, MISSOURI, ASSIGNOR OF ONE-HALF TO JAMES L. HOGIN, OF KANSAS CITY, KANSAS

AUTOMOBILE DOORLOCK

Application filed February 17, 1930. Serial No. 428,980.

My invention relates to improvements in automobile door locks.

One of the objects of my invention is to provide a door lock which has novel means for forcing a closed car door open when the lock handle is turned to release the bolt from the jamb, thus enabling a tight fitting door to be easily opened from the inside of the car.

10 A further object of the invention is to provide a novel lock which is simple, cheap, strong, durable, not likely to get out of order, which is readily adaptable to car door locks of common type, and which enables the lock handle to be swung from a bolt retracted position to a bolt locking position, in the type of locks in which the handle is employed to lock the door.

The novel features of my invention are 20 hereinafter fully described and claimed.

In the accompanying drawings, which illustrates the preferred form of my invention,

Fig. 1 is an elevation, partly broken away, of my improved door lock shown mounted 25 in a car door, with the bolt engaged with the door jamb, the jamb and door being shown in vertical section, and broken away, the lock handle being shown in solid lines in the unlocked position, and in dotted lines in the 30 bolt retracted position.

Fig. 2 is a section on the line 2—2 of Fig. 1, the lock being shown in plan looking at its upper end, and the bolt being engaged with the jamb and the door closed and push member retracted.

Fig. 3 is a view similar to Fig. 2, the bolt being retracted, and the push member having engaged the jamb and forced the door partly open.

40 Fig. 4 is an enlarged section on the line 4—4 of Fig. 1.

Fig. 5 is a section on the line 5—5 of Fig. 4. Similar reference characters designate simi-

45 lar parts in the different views.

1 designates a lock casing of usual type mounted on a car door 2, and having the usual bolt 3 retractible by an oscillative handle 4 from a recess 5 in a door jamb 6, having a usual vertical seat 7 at the inner side of 50 the door, when the latter is closed.

For forcing the door 2, when closed, toward the open position, when the handle 4 is swung to retract the bolt 3, I provide a push member, which has threaded engagement with the casing 1, and which comprises a 55 horizontal screw 8, which extends through and is rotative and axially slidable in the casing 1 and is adapted to have its inner end strike against the jamb seat 7. The casing 1 is provided on its inner side with a fixed 60 plate 9 having a circular row of recesses 10 in which are fitted the threads of the screw 8, Fig. 5.

When the screw 8 is turned counter clockwise, as viewed in Figs. 1 and 5, it will retract into the casing, to the position shown in Fig. 2. When turned clockwise, as viewed in Figs. 1 and 5, the screw 8 will project from the lock casing 1 and will strike the seat 7, thus forcing the door 2 toward the open position, thus assisting the operator in the car 70 to open the door.

For turning the push member or screw 8 to the position shown in Fig. 3, when the handle 4 is swung to retract the bolt 3 from the recess 75 5, the screw 8 is provided with a lost motion connecting means with the handle 4, comprising, as shown, the following described parts.

The screw 8 is provided with a crank arm 80 11 to which is pivoted a link 12 which is mounted on a screw 13 slidably mounted in a slot 14 in a crank 15, which is mounted on and oscillative with a horizontal shaft 16 with which the handle 4 is provided.

85 The screw 13 has on it a nut 17 which holds the link 12 on the screw.

A spring 18 encircling the push screw 8 bears against the casing 1 and against the crank arm 11 of the screw 8, and exerts a 90 tension tending to normally retract the crank arm 11 and screw 8 to the inner position, shown in Fig. 2, and in solid lines in Fig. 1. In this position of the parts, the handle 4, crank 15 and link 12 will be in the positions 95 shown in Fig. 2, and in solid lines in Fig. 1, with the connecting screw 13 at the left end of the slot 14, as viewed in Fig. 1.

When it is desired to open the door, the handle 4 is swung to the position shown in 100

dotted lines in Fig. 1, thereby moving the crank 15, link 12 and crank arm 11 to the positions shown in dotted lines in Fig. 1, which swinging of the crank arm 11 will turn the 5 push screw 8 clock-wise, as viewed in Fig. 1, thereby causing the push screw 8 to move out of the casing 1 and against the jamb seat 7, as in Fig. 3, thus pushing the door 2 to the partly open position shown in Fig. 3. The 10 door can then be easily pushed open from the inside of the car.

Sufficient loss motion is provided to permit the bolt 3 to be withdrawn from the recess 5 before the push screw 8 pushes the 15 door toward the open position.

When the handle 4 is released, it will be retracted to its initial position, shown in solid lines in Fig. 1, as will be the crank 15, by a spring in the casing, not shown, but which 20 is usually provided for this purpose.

Upon the retraction of the crank 15, the spring 18 will retract the crank arm 11 and push screw 8 to the position shown in Fig. 2 and in solid lines in Fig. 1.

25 When it is desired to lock the door, the handle 4 is swung to the left, from the position shown in solid lines in Fig. 1 thus swinging the crank 15 to the left from the position in which it is shown in solid lines in Fig. 1.

30 Such movement to the left of the handle 4 and crank 15 will actuate mechanism, not shown, to lock the door.

The provision of the slot 14 in the crank 15 and the screw 13 slidably mounted in said 35 slot, enables such locking movement of the handle 4 and crank 15 without affecting the position of the link 12 or crank arm 11. This lost motion connection of the crank 15 with the link 12, however, does not interfere with 40 the actuation of the push screw 8 to push the door toward the open position, when the handle 4 is swung from the locked position to the position shown in dotted lines in Fig. 1.

I do not limit my invention to the structure 45 shown and described, as many modifications, within the scope of the appended claim, may be made without departing from the spirit of my invention.

What I claim is:—

50 In a car door lock, the combination with a lock casing, a bolt in said casing, and a handle for retracting said bolt movable from a bolt retracted position to a bolt locking position, of a push member rotative and axially 55 slidable in and having threaded engagement with said casing such that, when turned in one direction, it will be adapted to push against a jamb so as to open a closed door associated with said jamb and carrying said 60 casing, said push member having a crank arm, a crank on and oscillative with said handle and having a slot, a link pivoted to said crank arm, means slidable in said slot connecting said crank with said crank arm for 65 turning said push member in said direction

and providing a lost motion connection between said crank and said link, and yielding means for so retracting said push member.

In testimony whereof I have signed my name to this specification. 70

ROBERT N. SMITH.
